(57) **CLAIM**

The ornamental design for an earring as shown and described.

DESCRIPTION

1. Earring

1.1 : Perspective view 1

1.2 : Perspective view 2

1.3 : Front

1.4 : Back

1.5 : Top

1.6 : Bottom

1.7 : Right

1.8 : Left

1.9 : Reference

The characteristic features of the design reside in the shapes as shown in the reproductions; the broken lines in the reproductions illustrate portions of the earring and the broken lines in 1.9 depicting an ear illustrate environmental structure. The broken lines form no part of the claimed design.

1 Claim, 9 Drawing Sheets
